HIGH-INTENSITY ARC LAMP FOR CONTINUOUS OPERATION

Hans Jakob Frey, Zollikerberg, Zurich, Switzerland, assignor to Edgar Gretener, Zurich, Switzerland

Application March 23, 1953, Serial No. 344,109

Claims priority, application Switzerland April 7, 1952

5 Claims. (Cl. 314—20)

The present invention relates to high-intensity arc lamps, particularly to blown-arc lamps for continuous operation.

In the arc lamps generally employed today replacement of carbon electrodes requires interruption of the arc current and thus of light generation. This is highly undesirable in particular cases of application, e. g. with searchlights, or cinema and television projectors.

Arc lamps have become known wherein the individual electrodes have mating ends which fit into each other in order to permit continuous operation, additionally a binding paste may be applied to these ends which is hardened by the heat of the arc in order to obtain a better mechanical and electrical connection of the individual electrodes. This will avoid disintegration of the electrodes when the separation gap enters into the arc, and an uninterrupted transmission of the arc current across this gap is to be achieved. Experience, however, has shown that by these means fluctuations or interruptions of light generation may not be avoided with absolute security.

The present invention has the object to overcome these difficulties and is related to a high-intensity arc lamp for continuous operation by employment of carbon electrodes, the mating ends of which may be inserted into each other and are covered with an electrically conductive binding paste fusible by heating. According to the present invention such a lamp is characterized by a heating device immediately disposed behind the electrode holder which effects fusing of the attached electrodes before they enter into the holder.

The present invention will now be explained with the aid of the attached drawing, wherein:

Fig. 1 schematically shows an embodiment of the present invention in perspective representation, and

Fig. 2 shows partly in a section the carbon electrodes employed in such a lamp.

In the lamp represented as embodiment of the invention by Fig. 1 the arc 1 is struck between the positive electrode 2 and the negative electrode 3. The crater 4 at the tip of the positive electrode represents the light source proper and is located in the focal point of the optical system, by ways of example of a concave mirror 5, which concentrates the light generated by the arc in a suitable manner, by ways of example in order to illuminate the aperture of a projector. The positive carbon 2 is supported in a holder 6 the "positive head," which also contains the contacts, mostly brushes, for admitting the arc current, and is advanced by transport rolls 7 in the well known manner as it burns away. Similar devices are provided for admitting current to an advancing the negative carbon 3, but which have not been shown in the drawing for the sake of clarity.

According to the present invention a heating device 8 is disposed immediately behind the electrode support, i. e. behind the positive head 6. This device may by ways of example be given the form of an electrically heated oven through which the electrodes pass on their way to the positive head.

2

The electrodes employed in such a lamp for continuous operation are schematically shown by Fig. 2. With high intensity arc lamps they customarily are composed of a pure-carbon shell 20 and a core which has an admixture of metal salts. To permit continuous operation, shell 20 and core 21 of the individual electrodes are displaced relatively to each other, so that on one side the core issues as plug 22, whereas on the other side a socket 23 is formed by the shell. The carbon electrodes thus have mating ends which fit into each other. These ends are covered with a binding paste which may be fused and rendered electrically conductive by heating.

If the lamp shown by Fig. 1 is fed with such carbon electrodes they are fused within the oven 8. As a consequence the arc is fed with what may be called a practically homogeneous electrode of "infinite length." This requires a suitable choice of the binding paste and a sufficiently high temperature within oven 8.

By fusing the electrodes before they enter into the holder, soiling of the current brushes by binding paste or combustion products thereof is avoided. Furthermore the employment of a separate oven permits to establish fusing of the electrodes under most advantageous conditions as the duration of heating and the temperature may be adapted to any requirements. If necessary the temperature may also be varied according to the predetermined program in correspondence with the advance of the separation gap. All this cannot be effected within the hitherto known lamps as in these lamps fusing is effected by the heat of the arc itself.

In the device according to the present invention fusing is furthermore effected before the carbon passes the current contact, e. g. a brush disposed on the electrode holder. This avoids contact disturbances caused by the formation of gas or drops. This may be brought about by evaporation or sweating out of the paste during fusing.

Additionally a scraping device may be provided which removes remnants of the paste issued from the gap during fusing before the carbon enters into holder 6. Such a scraping device 16 has schematically been shown in Fig. 1.

The present invention offers particular advantages if a "blown-arc" lamp is employed, wherein an arc stream issuing from the positive holder concentrically surrounds the positive electrodes. This arc stream has approximately the form of a hollow cone converging in direction towards the negative electrode. Thereby the arc discharge and the anode tail flame are aligned and concentrated into the cylindrical space in front of the positive crater. This is schematically indicated in Fig. 1 wherein the positive holder additionally acts as air nozzle, having a ring shaped opening 9, from which a concentrical air stream 10 issues. An exhaust funnel 11 is provided on the negative side, which removes the arc stream and the flame gases. The air may be supplied to nozzle 9 as shown in Figure 3 of U. S. Patent No. 2,662,991 to Gretener, there being a common owner of the patent and this application.

With such arc lamps as is well known, extremely high current densities and correspondingly high light intensities may be achieved. The high current density, it is true, implies increased consumption, particularly of the positive electrode. Considering the limitation of the length of the single carbon imposed by the optical system of the lamps, this increased consumption entails an inadmissibly short burning period for a single carbon electrode. It is thus indispensable to have recourse to continuous operation.

In a blown-arc lamp on the other hand, the carbons burn with such uniformity that continuous rotation of the carbons during operation is not required. The combina-

tion of the present invention with a blown-arc therefore represents an extremely advantageous solution of high reliability of operation, as the electrodes fused by the heater device are not subject to mechanical stress. In contrast thereto, as is well known, other high-load high-intensity arc lamps require continuous rotation of the carbons in order to guarantee uniform consumption. The devices habitually employed for rotating the carbons exert high compression and torsion stresses, so that breaking of the fused gap may easily occur, and will cause interruption of operation.

As has been shown in Fig. 1, the heater device is preferably located within the shadow cone cast by the electrode holder 6, so that it does not cause additional disturbing shadows within the light beam reflected by mirror 5.

An arc lamp according to the present invention may also be constructed in such a manner that transport and insertion of carbon electrodes is effected automatically from a magazine. This is schematically shown in Fig. 1. A magazine 12 filled with new electrodes 13 is located at the rear of the positive electrode holder. The electrodes are urged upwards by a spring 14. The uppermost electrode is shifted into the opening of oven 8 by transport rolls 15. The speed of transport by rolls 15 is slightly higher than of rolls 7, so that fusing of the electrodes within oven 8 is effected under a certain pressure. Rolls 15 by way of example are driven through a slip clutch in order to avoid excessive wear of the advancing carbons. If the uppermost electrode has been transported so far that it issues from the magazine, the next electrode takes its place under the action of spring 14 and insertion of the ends is effected by rolls 15.

Preferably the carbons are employed in the position shown in Fig. 1, i. e. plug 22 forms the rear end of the preceding carbon, whereas socket 23 is located at the forepart of the succeeding carbon. Preferably a sufficient amount 24 of the binding paste is deposited within socket 23. By way of example, however, the socket 23 filled with paste may also be closed by a suitable cap 26 which is only pierced and thus opened when the carbon is inserted. Thereby soiling by leaking paste may be avoided during transport storage or in the magazine.

It may also be useful to provide lateral holes 25 in the socket 23. Through these holes excess of paste and its evaporation and combustion products generated during fusing may escape. If that is not possible bursting of the shell by the gases confined within the socket may occur.

As has been shown in Fig. 1 magazine and additional feeding means are also located within the shadow cone of the electrode holder, so that additional shadows are avoided.

In the preceding description means for continuous operation have been shown on the positive side. As has already been mentioned this offers particular advantages with lamps of highest current densities and correspondingly elevated consumption, which would entail inadmissibly short consumption periods of the individual electrodes with regard to the limitation of the length of the individual carbons imposed by the optical system.

The principle of the present invention may also be employed on the negative side. With regard to the considerably lower consumption of the negative electrode this will in general not be necessary, particularly if the rod-shaped electrode is replaced by a disk-shaped electrode, the arc terminating on the disk edge.

Lamps with disk-shaped electrodes which have become known attain a manifold period of operation in compari-

son with rod electrodes, due to the uniform distribution of consumption along the entire edge of the disk.

I claim:

1. In a high-intensity arc lamp for continuous operation achieved by the employment of carbon electrodes with mating ends which may be inserted into each other and which are covered with a binding paste conductively fusible by heating, an electrode holder for supporting the positive electrode and a heater device immediately disposed at the rear of said electrode holder which effects fusing of the electrodes inserted into each other before the separation gap enters into the arc.
2. In a high-intensity arc lamp for continuous operation achieved by the employment of carbon electrodes with mating ends which may be inserted into each other and which are covered with a binding paste conductively fusible by heating, an electrode holder for supporting the positive electrode and a heater device immediately disposed at the rear of said electrode holder which effects fusing of the electrodes inserted into each other before the separation gap enters into the arc, said electrode holder having an air nozzle by which an air stream is directed towards the arc and surrounding the arc as a hollow converging cone, whereby the arc discharge and arc flame are concentrated into the cylindrical space in front of the positive crater.
3. In a high-intensity arc lamp for continuous operation achieved by the employment of carbon electrodes with mating ends which may be inserted into each other and which are covered with a binding paste conductively fusible by heating an electrode holder for supporting the positive electrode and a heater device immediately disposed at the rear of said electrode holder which effects fusing of the electrodes inserted into each other before the separation gap enters into the arc, said heater device being located within the shadow cone cast by the electrode holder, whereby additional shadows are avoided.
4. In a high-intensity arc lamp for continuous operation achieved by the employment of carbon electrodes with mating ends which may be inserted into each other and which are covered with a binding paste conductively fusible by heating an electrode holder for supporting the positive electrode and a heater device immediately disposed at the rear of said electrode holder which effects fusing of the electrodes inserted into each other before the separation gap enters into the arc, and a scraping device located in between the heater and the electrode holder for removing remnants of paste left after fusing.
5. In a high-intensity arc lamp for continuous operation achieved by the employment of carbon electrodes with mating ends which may be inserted into each other and which are covered with a binding paste conductively fusible by heating, an electrode holder for supporting the positive electrode and a heater device disposed immediately at the rear of said electrode holder which effects fusing of the electrodes inserted into each other before the separation gap enters into the arc, a magazine for new electrodes and additional transport means which effect automatic transport and insertion of the carbon electrodes from the magazine.
